(57) **CLAIM**

The ornamental design for a storage shelf as shown and described.

DESCRIPTION

FIG. 1 is a front, right and top perspective view of a storage shelf showing my new design;

FIG. 2 is a rear, left and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a front, right and top disassembled perspective view thereof;

FIG. 10 is a front, right and top perspective view of the top part of the storage shelf shown separate for completeness of illustration; and,

FIG. 11 is a rear, left and bottom perspective view of the top part of the storage shelf shown separate for completeness of illustration.

The broken lines illustrate portions of the article that form no part of the claimed design.

1 Claim, 11 Drawing Sheets
